UNITED STATES PATENT OFFICE

2,584,008

CONTAINER

James C. Fioretti, El Paso, Tex.

Application March 5, 1948, Serial No. 13,121

9 Claims. (Cl. 220—20.5)

1

This invention relates to new and useful improvements in containers and the primary object of the present invention is to provide a container including a pair of interconnected cup members connected by a passage and embodying novel and improved valve means for selectively opening and closing the passage so that liquids may be poured independently from the cup members or simultaneously poured from the chambers.

Another important object of the present invention is to provide a container including a pair of liquid holding cup members which are connected by passage wherein there is mounted a control valve, and novel and improved means for selectively activating the valve to an open and closed position.

A further object of the present invention is to provide a container for liquids that is extremely small and compact in structure and the parts of which are quickly and readily assembled or disassembled facilitating the convenient inspection or cleaning of parts.

A still further aim of the present invention is to provide a container that is simple and practical in construction, strong and reliable in use, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the present container;

Figure 2 is a longitudinal vertical sectional view of the present invention taken substantially through the center of Figure 1;

Figure 3 is a top plan view of Figure 1; and

Figure 4 is a transverse horizontal sectional view taken substantially on the plane of section line 4—4 of Figure 2.

Referring now to the drawings in detail, wherein for the purpose of illustration, there is disclosed a preferred embodiment of the present invention, the numeral 10 represents a substantially cylindrical container of preferably plastic material generally, comprising a lower cup member or chamber 12 and upper cup member or chamber 14. The open upper end 16 of the lower cup member 12 is internally threaded to receivably engage the externally threaded reduced bottom wall 18 of the upper cup member 14.

2

The bottom wall 18 of the upper cup member 14 is formed with an annular, beveled valve seat 20 which communicates with a passage 22 provided in a substantially spherical support 24 that is formed with perforations 26. The lower portion of the spherical support 24 is provided with an internally threaded opening 28 that threadingly engages the externally threaded upper end 30 of a substantially cylindrical, perforated strainer member 32 having an integral substantially frusto-conical lower end portion 34 which is also formed with perforations 36.

Slidably positioned in a guide opening 38 formed in the thickened wall 40 of the upper chamber 14, is a plunger or operating rod 42 which is provided with a reduced inner end 44 that extends into the lower chamber 12 and terminates adjacent a guide channel 46 integrally formed with the spherical support 24.

Pivoted loosely within the guide channel 46 is an actuating lever or link 48 one end 50 of which is disposed within the interior of the spherical supports 24, and the remaining end 52 of this lever 48 is slidably and pivotally connected to the inner extremity of the reduced inner end 44 for the plunger 42. The end 50 of the lever 48 is loosely received in an opening 54 formed in the stem portion 56 of an annular, beveled valve 58 that is normally positioned in the valve seat 20.

Receivably engaging an internally threaded socket 60 provided in the lower free end of the stem portion 56, is the reduced externally threaded end 52 of a rod or stem 64 having a beveled substantially frusto-conical valve or plunger head 66 integrally formed with its remaining end for frictional engagement in the valve seat 34.

Biased between an annular shoulder 68 within the guide opening 38 and the annular shoulder 70 formed on the plunger 42, is a coil spring 72 that normally retains the plunger in a raised position and the valves 58 and 66 normally in a closed position in the seats 20 and 34.

Integrally formed with the outer periphery of the upper chamber 14, is a holding lip or lug 74 that is adapted to be received in a notch or recess 76 formed in the plunger 42 adjacent a finger engaging ring 78 fixed thereto for holding the plunger 42 in a lowered position and the valves 58 and 66 in an open position.

In practical use of the present invention, a selected fluid is first placed in the lower cup member 12 and then the upper cup member 14 is applied to the lower cup member 12 and also filled with a selected fluid. To discharge the fluid from the upper cup member 14 the container is merely

tipped with the valves 58 and 66 in a closed position. To discharge the fluid in cup member 12, the plunger 42 is depressed to a locked position which will effect an opening of the valves 58 and 66 and the container is conveniently tipped. To mix and discharge the fluids from both cup members 12 and 14, the plunger is depressed several times and left in locked position which leaves the valves 58 and 66 in an open position and the container is conveniently tipped.

Having described the invention, what is claimed as new is:

1. A container comprising threadingly connected upper and lower cup members, said upper cup member having a bottom wall supported on the upper end of the lower cup member and an opening in said bottom wall, a perforated support integrally formed with the bottom wall and depending therefrom into said lower cup member, a strainer removably carried by and depending from said support and disposed entirely within said lower cup member, a valve member having a head portion adapted to close the opening in said bottom wall, said valve member including a stem extending downwardly into said strainer, a rod slidably mounted in said strainer and secured to the lower end of said stem for movement therewith, said rod having a lower end, a plunger head secured to the lower end of said rod, means for actuating said valve member, and means urging said valve member to a closed position.

2. A container comprising inter-connected upper and lower cup member, said upper cup member having a bottom wall supported on the upper end of said lower cup member and an opening in said bottom wall, a perforated support integrally formed with the bottom wall and depending therefrom into said lower cup member, a strainer removably carried by and depending from said support and disposed entirely within said lower cup member remote from the upper cup member, a valve member having a head portion located above the bottom wall and adapted to close the opening in said bottom wall, said valve member including a stem extending downwardly into said strainer, a rod slidably mounted in said strainer and secured to the lower end of said stem for movement therewith, a plunger head mounted on said rod, said upper cup member having an inclined bore therein, a plunger slidably received in said bore, a link pivoted on said support and having one end pivoted to said plunger, an opening in said stem receiving the free end of said link, means acting on said plunger and normally urging the valve member to a closed position, and means engaging said plunger for holding the valve member in an open position.

3. The combination of claim 2 wherein said last named means includes a lug projecting from the outer surface of said upper cup member, said plunger having a recess adapted to receive said lug upon sliding movement of said plunger in one direction.

4. A container comprising upper and lower inter-connected cup members, a passage in the lower wall of the upper cup member establishing a communication between the cup members, strainer means carried by and depending from the upper cup member and extending well into the lower cup member, said strainer means communicating at its upper end with the passage, valve means for selectively opening and closing the passage, a slideable plunger carried by the upper cup member for actuating the valve means, means acting on the plunger and normally retain-

ing the valve means in a closed position, means for holding the valve means in an open position, and a plunger head positioned in said strainer means and attached to and movable with said valve means.

5. The combination of claim 4 wherein said means for holding the valve means in an open position includes a holding lug integrally formed with the outer surface of said upper cup member, and a lug recess provided in the plunger for receiving the holding lug.

6. A container comprising a lower cup member open at its upper end, an upper cup member removably carried by the upper end of the lower cup member, a hollow support depending from the upper cup member and extending downwardly into the lower cup member, a strainer removably carried by and depending from the support, a passage leading from the lower cup member to the upper cup member, a valve for controlling the flow of liquid through the passage, a plunger slidably carried by the upper cup member, a pivotal link carried by the support and connecting the plunger to the valve, spring means recessed in the wall of said upper cup member and urging the plunger in one direction for normally retaining the valve in a closed position, means carried by the upper cup member for holding the valve in an open position, and a stem depending from said valve and slidably received in said strainer, said stem having an enlarged lower end portion.

7. A container comprising a cylindrical body composed of upper and lower cup members, said cup members being substantially equal in diameter, said upper cup member including a bottom wall removably secured to the upper end of the lower cup member, a strainer depending from the bottom wall and positioned in the lower cup member, said bottom wall having an opening therein in registry with the strainer, valve means for selectively opening and closing the opening, and a plunger slidably received in the strainer and always remaining entirely within the strainer throughout opening and closing movement of the valve means.

8. A container comprising a cylindrical body composed of upper and lower cup members, said cup members being substantially equal in diameter, said upper cup member including a bottom wall removably secured to the upper end of the lower cup member, a strainer depending from the bottom wall and positioned in the lower cup member, said bottom wall having an opening therein in registry with the strainer, valve means for selectively opening and closing the opening, said valve means including a stem extending into the strainer, a rod attached to said stem and entering the strainer and an enlargement on the lower end of said rod.

9. The combination of claim 8 and a valve actuator carried by said upper cup member and connected to said stem.
